UNITED STATES PATENT OFFICE.

JULIAN EARL MONTGOMERY, OF WHEELING, WEST VIRGINIA.

LUBRICANT-HEATING APPARATUS.

1,281,993.

Specification of Letters Patent.

Patented Oct. 15, 1918.

Application filed May 21, 1918. Serial No. 235,911.

To all whom it may concern:

Be it known that I, JULIAN EARL MONTGOMERY, a citizen of the United States of America, and resident of Wheeling, county 5 of Ohio, and State of West Virginia, have invented certain new and useful Improvements in Lubricant-Heating Apparatus, of which the following is a specification.

This invention relates broadly to lubricant-heating devices, and it has for its primary object to provide an apparatus adapted for mounting in a convenient position upon a roll-housing of a sheet, tin or jobbing mill whereby the heavy grease or other 15 lubricant employed on the roll necks and bearings may be maintained at a proper degree of fluidity for ready and economical application.

A further object is to provide a grease-pot and a hanger therefor which are so constructed that they may be readily disposed in associated relation upon a roll housing, and that the pot may be removed and replaced with a minimum of inconvenience 25 and loss of time.

With these and other objects in view, the invention resides in the features of construction, arrangement of parts and combinations of elements which will hereinafter be fully 30 described, reference being had to the accompanying drawings, in which—

Figure 1 is a front elevation of a roll housing, showing my invention applied thereto;

Fig. 2 is a side elevation of the same;

Fig. 3 is an enlarged view of the grease-pot, partly in side elevation and partly in section;

Fig. 4 is a section on line 4—4, Fig. 3; 40 and—

Fig. 5 is a top plan view of said pot.

Referring to said drawings, in which like designating characters distinguish like parts throughout the several views—

1 indicates an open-top grease-container which is preferably of approximately rectangular form in top plan and which has a lateral encircling flange 2 adjacent to its upper edge adapted for seating closely upon 45 and to be suitably attached to a similar flange 3 located about the upper edge of a casing 4 within which the body of said container depends. The body portions of said container 1 and said casing 4 are relatively 50 disposed to provide an intermediate container-encircling space or chamber 5 into

which steam is directed for imparting heat to the grease or other contents of said container.

To provide an increased surface area exposed to the heating influence of steam admitted to the steam chamber 5, thus increasing the efficiency of the pot for grease-melting purposes, and, further, to provide for a more nearly uniform heating of the contents of the container—that is, a more effectual heating of that portion of the contents which would otherwise be remote from the container walls—the said container has its bottom formed with a central flute-like crimp or fold 6 which stands elevated a suitable distance and which has its walls separated to provide a pocket or channel 7 that forms a part of, or communicates with, said steam chamber.

Projecting horizontally outward from each of the opposite ends of the casing 4, and preferably constituting integral extensions of the flange 3, are two supporting lugs 8 which are adapted to seat upon a pair of horizontally disposed parallel arms 9 composing parts of a hanger 10 by means of which is suspended the pot composed of the container 1 and casing 4 hereinbefore described.

Said hanger 10 has a body of approximately inverted-U form adapted to be detachably mounted upon the side of a roll housing 11, as by engagement of an integral eye-member 12 carried thereby with a hook 90 or bolt 13 rigidly carried by said housing. Said arms 9 constitute angularly disposed extensions of the lateral members of said hanger body and are terminated at their outer ends by upturned terminals 14 whereby chance displacement of the mounted pot is effectually prevented.

It will be noted that the position occupied by the pot, supported as aforesaid, is such with respect to the rolls to be lubricated that 100 application of the melted grease by means of the swabs usually employed may be conveniently accomplished.

The casing 4 has flat-faced parallel transverse ribs 15 on its bottom adapted to seat 105 upon the floor when the pot is lowered thereon, as when the container is to be filled, said ribs serving to support the pot in upright position.

Steam is conducted to the upper part of 110 the steam chamber 5 through a pipe 16 and is conducted from said chamber through a

- pipe 17 leading outward through the side of the casing. The steam employed may be used to heat the pots for a plurality of mills in succession by connecting the same up in 5 groups, employing the exhaust pipe 17 of the first as the supply pipe for the next, and so on, in which case, as is apparent, a single suitably located steam trap will suffice for all.
- 10 A relief valve, as 18, whereby excess steam pressure may be released from the chamber 5 when required, may be employed.

What is claimed is—

- 15 1. The combination with a roll housing, of a hanger mounted on the side thereof adjacent to the roll bearings, a grease pot removably mounted upon said hanger, said pot comprising an outer casing and a grease container disposed within said casing and having its walls spaced from those of said casing to provide an intermediate steam chamber, means for conducting steam to said chamber, and means for conducting steam from said chamber, said grease pot having lugs at its ends for resting upon said hanger.
- 20 2. The combination with a roll housing, of a hanger mounted on the side thereof adjacent to the roll bearings, said hanger comprising a body of inverted-U shape having its opposite members bent to form parallel outwardly extending horizontal arms, and a grease pot removably mounted on the arms of said hanger, said grease-pot comprising a casing having lugs for seating upon said

arms, and a grease container disposed within said casing and having its walls spaced from said casing to form an intermediate steam chamber.

3. The combination with a roll housing, of a hanger mounted on the side thereof adjacent to the roll bearings, said hanger comprising horizontal outwardly directed supporting arms, and a grease pot having external lugs removably seated upon said arms, said grease pot comprising a casing 45 and a grease container suspended within said casing, said container having its walls spaced away from those of said casing to form an intermediate steam chamber.

4. The combination with a roll housing, of a hanger mounted on the side thereof adjacent to the roll bearings, said hanger comprising horizontal outwardly directed supporting arms, and a grease pot having external lugs removably seated upon said arms, 50 said grease pot comprising a casing having a curved bottom provided exteriorly with seating ribs, and a grease container suspended within said casing, said container having its walls spaced away from those of 55 said casing to form an intermediate steam chamber.

In testimony whereof, I affix my signature in presence of two subscribing witnesses.

JULIAN EARL MONTGOMERY.
